Primary Examiner — Derrick E Holland

(57) **CLAIM**

The ornamental design for solar module, as shown and described.

DESCRIPTION

FIG. 1 is a perspective view of a solar module;
FIG. 2 is a front elevation view thereof;
FIG. 3 is a back elevation view thereof;
FIG. 4 is a top view thereof;
FIG. 5 is a bottom view thereof;
FIG. 6 is a first side view thereof; and,
FIG. 7 is a second side view thereof.
The broken lines shown represent the portions of the solar module that form no part of the claimed design.

1 Claim, 5 Drawing Sheets
